(57) **CLAIM**

The ornamental design for a portion of display panel or screen with an animated graphical user interface as shown and described.

DESCRIPTION

FIG. 1 is a front view of a portion of a display panel or screen with a first one of first display images of an animated graphical user interface showing our new design; and FIG. 2 is a front view of a portion of the display panel or screen with a second one of the first display images thereof; FIG. 3 is a front view of a portion of the display panel or screen with a third one of the first display images thereof; and,

FIG. 4 is a front view of a portion of the display panel or screen with a fourth one of the first display images thereof. The appearance of one of the first display images transitions sequentially between FIGS. 1-4. The process or period in which one of the first display images transitions to another one of the first display images forms no part of the claimed design.

The outermost dot-dash broken lines shown in the drawings illustrate the portion of the display panel or screen that form no part of the claimed design. The even dash broken lines illustrate a set of portions of display panels or screens with animated graphical user interface and form no part of the claimed design.
